UNITED STATES PATENT OFFICE.

HENRY S. SATTERLEE, OF NEW YORK, N. Y.

SOUND AMPLIFIER.

Application filed September 28, 1923. Serial No. 665,258.

This invention relates to an improved device and method for the amplifying and distributing of sound waves as, for example, those produced by a vibrating diaphragm or similar sound generators. The preferred form of the invention illustrated is particularly adapted to the amplification and distribution of sound waves reproduced for auditory reception, as exemplified in the 10 mechanically operated diaphragm of the phonograph, and in the electro-magnetically operated diaphragm of the telephone receiver, and it is specially applicable to use as a loud speaker in radio telephony.

15 In the drawings accompanying this specification and of which they form a part, I show:

Fig. 1, a selected form of sound amplifier, or resonator, and which, for descriptive purposes in this instance, I have denoted by three parts, viz: the straight portion extending from 7 to 2, the central portion extending from the point of initial curvature at 2 around to a point in the general position 25 of 5, and an end portion extending from 5 to the termination of the spiral and the adjoining flare 17. These portions may be continuous to form an integral whole or certain parts may be made separately and cemented, or joined, together in an appropriate manner as may be best suited to the conditions of use and manufacture. In the development of the spiral of the amplifier, as shown in Fig. 1, both the inner and outer 30 borders have a common centre or origin at 1. The broken lines 1—2, 1—3, 1—4, 1—5, 1—6, 1—8, 1—9, 1—10 are radii vectors from the centre 1 to the spiral borders.

Fig. 2 is a circle; the limiting case of a 40 logarithmic spiral.

Figs. 3 and 4 show the evolution of the spiral and refer particularly to later mathematical computations.

The invention includes two principal elements; a horn, and an enclosing material for the horn. The horn is characterized by having its curvature especially designed with respect to the volumetric expansion which has been found to be most advantageous for a conical resonator, the theoretical mathematical limitations of the optimum

to conform to the physical requirements for maximum reflection, that is to say of minimum absorption of sound wave energy, and at the same time to limit the resonance to that of the air contained in the cavity to the exclusion of any audible resonance produced by the walls of the horn itself. These features are combined to reproduce all proportionate elements of sound exactly as propagated at the source; a decided improvement 65 over other forms of resonators.

One of the main requisites of a resonating tube or horn, designed for the amplification of sound waves, is that it shall have adequate length to respond sufficiently to the 70 longest wave lengths which it may be desired to reproduce, which wave lengths extend to the lower tones of the musical scale. That is to say, the sound wave length range which may be considered, for practical purposes, lies between the frequencies of 129 or C₂ and 20,480 or E₉, the wave lengths corresponding to these frequencies varying from approximately 48 inches to a small fraction of 1 inch. The transmission of so full a range of musical tones necessitates a length of amplifying horn sufficient to conform to certain requirements. For instance, it has been found that a horn less than 36 inches in length, while functioning well for the higher notes, will not give an adequate response to the lower notes of the musical scale, whereas one over 48 inches in length, while showing no apparent change in the functioning for higher notes, gives an entirely satisfactory response to the lower tones. The explanation of this is that the shorter length resonator can only reproduce the over tones of any notes which are below 80 its range. In other words, a note, which has a wave length longer than the horn, is suppressed and the next higher harmonic which is the octave, and other partials are sounded. This obviously leads to a false rendition of the quality of the original source of sound employed and when the shorter and longer horns are compared side by side, using the same sound generator, it may be observed that, in addition to the change of quality, there is a definite acoustic sensation of an 85 octave difference in pitch.

monics a different form of distortion will be produced, depending upon the relative volume of the partials which are sounded.

Amplifying horns, when analyzed by laboratory methods, show characteristics which are evidenced by their oscillograms, or photographic tracings of sound wave transmission, which indicate that there is a definite fundamental resonance corresponding to the 10 length and shape of the individual horn, which tends to dominate the response for certain wave lengths and also an increase of response at certain wave lengths which is due to the fundamental resonance of the dia- 15 phragm of the generator.

The distortion due to these two resonance factors is very noticeable with resonating tubes having a terminal opening equal or greater than half of their length. Techni- 20

20 technically speaking, an amplifying horn may be considered as enclosing an air column which is the actual resonator of the sound waves. This air resonator functions according to its size and shape and there is an additional factor sometimes noticeable, depending on the material of the horn; this last is an adventitious factor, due to the intrinsic resonance, or vibration, of the walls of the horn itself and may be recognized in the 25

30 metallic sound which is associated with the ordinary tin megaphone and with most metallic horns. I have found that, to give most satisfactory results as a distortionless sound amplifier, a straight resonating tube should 35 be more than 36, and preferably between 48 and 65 inches in length and should have an outlet of a diameter equal to about one-sixth of the slant length of a corresponding straight cone. This would be equivalent to 40

40 considerably less than one-sixth of the length of curvature of a cone which is coiled upon itself. For the ratio of base diameter to slant length in a straight cone is more essentially, for present purposes, the ratio of 45 base area to total volume; and when a cone of given length is coiled into a spiral, the volume is diminished accordingly, although the slant length function is preserved in the outer course of the spiral. To preserve the 50

50 optimum ratio of base area to total volume the diameter of the base must therefore be reduced in the spiral. This results in a modification of the base diameter to slant length ratio when dealing with a curved 55 resonator. The problem of so coiling the resonating tube as to preserve the acoustic features of a straight cone as far as possible and to avoid distortion by phase interference and loss of wave energy by damping factors 60

60 of reflection, has been the subject of original investigation by me from a mathematical standpoint and of which I treat later.

I have accordingly designed the curves of 65 the tube, or horn, upon a carefully calculated basis to suit the special requirements as out-of

lined above and have adopted the principle of the logarithmic spiral as the best solution of this curve. In the logarithmic or equi- 70 angular spiral, the angle formed by the tangent to any radius vector is a constant, shown as angle α in Figs. 2 and 3. This angle determines the ratio of expansion of the spiral. The value of this constant is important for my purpose as determining the relation between the total length of the resonating tube 75 and the diameter available for its outlet. I have found that the constant angle α of 80 degrees 5 minutes produced the desired result, but I do not wish to confine myself to this particular angle as any values between 75 and 83 degrees or even below and above this might be selected in choosing a 80 curve for different requirements as to length and volume of resonating tube and bulk of the enclosing material which would be best 85 adapted to any selected sound generator.

As will be seen from Fig. 1, this constant angle applies in developing the curve of both inner and outer borders of the tube, or resonator, and the relation of these two 90 curves is a matter for special selection as will be brought out in a later mathematical treatment.

In development, the tube is symmetrical in cross section, taken along the line of any 95 radius vector, and for the purpose of this specification, such section is assumed to be circular, so that the logarithmic function obtains here in the expansion of a circular cross sectional area, although it is evident that a 100 variety of cross sections might be selected and used effectively.

The straight portion of the resonator, 7 to 2 in Figure 1, conforms in circumference 105 at 2 with the spiral portion of the resonator and may be either a cylinder or a conical tube; a truncated cone being preferably shown with the truncated extremity 7 arranged to fit the sound generator. The slant 110 of this truncated cone approximates a tangent to the spiral tube at the juncture 2, that is, it makes the aforesaid angle α with the radius vector 1-2 to the outer border at this point.

In Fig. 1 dotted lines between the points 115 15 and points 16 represent the lines of propagation of the wave front from the sound generator. As indicated, these are reflected from the curved wall of the spiral in a manner to make the angles of reflection equal to the angles of incidence upon the tangent to the spiral at the points impact as shown, for example, at points 15 and points 16 in Figure 1.

The inner boundary of the resonating tube 125 at its initial curve is specially designed to give these reflected rays free passage. From the point of juncture with the straight portion 7-2, up to 8, another logarithmic spiral 130

is employed for this inner boundary and is developed from the same center or point of origin, 1. From a practical standpoint it has been found that this design for the inner boundary at the initial curve entirely prevents the choking effect which is otherwise noticeable in effecting an abrupt change of direction near the source of energy in a spiral resonator. In Figure 1, all portions of the resonator are shown in the same plane in order to demonstrate the nature of the curve in a simple manner. Obviously however it is necessary for clearance, to offset the first portion of the tube. This may be effected by rotation upon an axis 11-12 which is taken normal to 1-3 and upon an axis 13-14 which is taken normal to 1-4. A twenty degree shift on each of these axes will give the required clearance.

Beyond the radius vector 1-8-4, as shown in Figure 1, the inner boundary of the resonator is a logarithmic spiral exactly equal to that forming the outer boundary but with an angle of retardation, as shown in this instance, of approximately 270 degrees. This angle of retardation determines the cross sectional area and is an essential factor in adjusting the volumetric capacity of the resonator. It may therefore be varied to suit requirements. The total angle of revolution of the spiral portion of the resonator, and consequently its length, is governed by the range of the sound to be reproduced and the condition to be met and therefore will also be variable. In the resonator of Figure 1, this angle is shown as 600 degrees.

As previously stated an important feature of my invention is the substance of which the resonator is made, and for which a dense, non-porous material is used. By way of illustration and because it has been satisfactory in practice, I have fixed upon plaster of Paris for this purpose, although it will be understood that I do not confine myself to this substance alone as many similar gypsum cements and other materials do equally well and any kind of dense material such as metal, synthetic resins or cements other than gypsum cements would be available for special purposes. Gypsum cement, when first cast, is relatively dense owing to the moisture present and in this condition serves well to reflect a maximum of sound wave energy. However, porosity develops with the evaporation of the moisture and the dry gypsum has a tendency to crumble under the physical impact of the sound waves. To avoid this, the casting, as first made, may be heated to drive off the moisture and then impregnated with waxy or resinous material or a mixture of such materials or any other materials which will render it permanently non-porous and give maximum density in a permanent form. The resonator so constructed forms a dense, smooth-walled and relatively

massive enclosure which directly limits the vibration of the wall. I have found it important and, in most instances, preferable to have the volume of the wall material equal to or in excess of the air volume enclosed by the curve. This I have found avoids any resonance resulting from the wall.

For convenience in manufacture, and because of the lateral twist which is required to offset the straight portion for clearance of the outer convolutions, it has been found advisable to cast in metal that portion of the tube which extends from 7 to 4 and to imbed it in the plaster of Paris or such material as may be used for the main portion of the resonator. This union forms a dense-walled non-vibrating central core at the commencement of the spiral. In this first portion of the spiral, the physical impact of the sound waves is a maximum but when these waves have reached the more expanded portion of the resonator, as may be approximately indicated at 5 in Figure 1, they have lost a portion of their energy of impact through expansion and the influence of various damping factors. Consequently the thickness of the resonator wall from this point on need not be as dense or as massive as in the first portion, but the same spiral development is continued to where a final and slight flare is provided at the termination of the spiral, said flare being shown at 17 in Figure 1. The size of this flare is of particular importance in the final adjustment of the volumetric ratio.

In designing an air resonator for use with any special type of sound generator, the wave energy production capacity of that generator should be taken into account. It is obvious that these generators will vary and that more powerful ones are required to fully energize an air resonator of large volumetric capacity than would be the case with resonators of small capacity. In my method of design, a predetermined volumetric range of capacity is chosen and which is suitable to the sound generator to be employed. Within this range is selected, by mathematical formulæ to be demonstrated later, a logarithmic spiral tube having a total volume of from 15 to 25 per cent less than the predetermined total volume.

This reserved volume is then added in the flare, the extreme diameter of which is restricted to not more than a 50 per cent increase over the diameter of the resonator at the termination of the spiral. I restrict the extreme diameter of the flare for the following reasons. The flare for the end correction of parallel wall pipes, originally formulated by Helmholtz, has the ratio

$$\frac{R}{R'} = \frac{1}{\sqrt{2}}$$

where R is the lesser radius and R' the

extreme radius of the flare. This represents an increase of 41.42 per cent in diameter and is the degree of flare usually employed in musical instruments of the conical type.

- 5 In the usual type of resonator, or amplifier, the ratio of the flare often runs as high as 400 or 500 per cent which I believe is done in order to give volumetric capacity in the flare rather than to employ a greater 10 length in the amplifier which would otherwise be necessary. I maintain that it is better to secure volumetric capacity by increased length and to assign to the flare only a small percentage of this capacity; 15 preferably 20 per cent or less. Theoretical investigation and practical experiment lead me to believe that, where there is sufficient length in a true logarithmic spiral resonator, no flare is necessary and need only be 20 sorted to for the incidental purpose of adjusting the total volumetric capacity of the resonator to the energy capacity of the sound generator. My investigations reveal that a flare has very little, if any, distributive 25 value in conjunction with my resonator.

In the following are brought out the formulæ used in the determination of my logarithmic spiral resonator, the mathematical procedure necessary to produce the effects 30 set forth in the preceding description.

The polar equation of a logarithmic spiral may be written—

$$R = e^{\theta \cot \alpha} \quad (1)$$

- 35 where R is the radius vector, e the Napierian base, θ the polar angle of revolution in radians and α the constant angle formed with the radius vector by the tangent to the spiral. 40 If R be any known radius vector and α known, any other radius vector, R' , may be found for any known value of θ ; or, any unknown value of θ may be found from known values of R and R' by arranging 45 the formula thus:—

$$\frac{R'}{R} = e^{\theta \cot \alpha} \quad (1^*)$$

where θ is the polar revolution in radians 50 between R and R' .

The length of any logarithmic spiral may be determined by the formula:—

$$L = R \sec \alpha = \frac{R}{\cos \alpha} \quad (2)$$

Figure 2 and Figure 3 represent tangents drawn to radius vectors enclosing an angle θ of 90 degrees. Figure 2 is a circle; the 60 limiting case of the logarithmic spiral. Fig-

stant and consequently its supplement, β , is constant; also $\phi + \omega = \beta$ and $\phi' + \omega' = \alpha$ and in the quadrilateral OPTQ, since θ equals 90 degrees, ψ must also equal 90 degrees. It follows that $\theta = \omega + \omega'$ and $\psi = \phi + \phi'$ and the ratios

$$\frac{\phi}{\omega} \text{ and } \frac{\phi'}{\omega'} \quad 70$$

vary inversely with θ .

In the spiral, $\frac{\omega'}{\omega}$ is a constant κ , depending upon α being constant, and κ is therefore a function of α .

In the circle, Figure 2, $\alpha = 90^\circ$ and $\omega = \omega' = \phi = \phi' = 45^\circ$ and the ratio

$$\frac{\omega'}{\omega} = 1 = \kappa \quad 80$$

Now in Figure 4, for example, the logarithmic spiral has the value for α of 77.55775 degrees.

From this value of α the angles ω and ω' may be evaluated as follows:—By equation (1*) it may be shown that, for $\alpha = 77.55775^\circ$ and $\theta = \frac{\pi}{2}$ radians (that is 90 degrees as shown in Figure 3) when $OP = 1$, $OQ = \sqrt{2}$ or 1.4142. Now the ratio

$$\frac{OQ}{OP} \quad 95$$

is $\tan \phi$ therefore $1.4142 = \tan \phi$ and $\phi = 54.735611^\circ$. Now $\omega = \beta - \phi$ and β (the supplement of α) is 102.44225° , consequently ω is evaluated as 47.706639° and ω' , the complement of ω , is evaluated as 52.293361° . Thus we have established for this angle α the ratio

$$\frac{\omega'}{\omega} = \frac{42.293361}{47.706639} = \frac{0.8865299}{1} = \kappa \quad 105$$

By algebraic proof it may be shown that the polar angles of revolution θ between points of incidence of the reflected rays develop the same ratio successively as has just been shown for successive values of ω that is to say $\frac{\theta'}{\theta} = \kappa$.

For $\theta = \omega + \kappa \omega$ and

$$\theta' = \kappa \omega + \kappa (\kappa \omega) = \kappa (\omega + \kappa \omega)$$

therefore $\theta' = \kappa \theta$ or $\frac{\theta'}{\theta} = \kappa$. The summation of 120 a series of θ representing the total revolution

Likewise a series giving the summation of the angles of reflection may be expressed: 45

$$\Sigma_n \omega = \omega_1 + \kappa \omega_1 + \kappa^2 \omega_1 + \kappa^3 \omega_1 + \dots + \kappa^{n-1} \omega_1 \quad (4)$$

The last term of the above may be expressed as an equation:

$$\omega_n = \kappa^{n-1} \omega_1 \quad (5)$$

- 5 By substituting the proper value for κ in the last term of equation (3) the point of incidence of the n th, or say the final, reflection may be determined and likewise by substitution for κ in equation (5) the value 10 of the n th or final angle of reflection may be found, provided, either that the point of first incidence and first value of θ are known, or that the point of first incidence and the first angle of incidence ω_1 are known.
- 15 The volume of a logarithmic spiral tube of circular vectorial cross section may be determined by the following formula, which is an application of the volumetric theorem of Pappus for solids of revolution to formula (2):—

$$\frac{R+r \tan \alpha}{2} \times \left(\frac{R-r}{2} \right)^2 \pi = V \quad (6)$$

- 25 Where R is the final or maximum radius vector to the outer limiting curve and r the final or maximum radius vector to the inner limiting curve and V the required volume.
- 30 In this equation, the expression $\frac{R+r}{2} \tan \alpha$ represents the length of the centroid or path described by the centre of mass of the figure of revolution, which is a circle; and the length of this axis is comparable to the altitude of a cone.

- In computing the volume of our resonator, as shown in Figure 1, the volume of a hypothetical continuation of the spiral from the point of junction with the straight portion of the tube at 2, Figure 1, to the point of origin, 1, is first obtained by this formula and is subtracted from the total volume of a complete spiral tube as computed by the same formula. In its place is added the volume

of the conical or cylindrical portion which 50 forms the connection with the generator.

For the purpose of comparison with a straight cone of equal base and slant length the following formulas are used:—

$$\frac{R-r}{2} = \sin U \quad (7)$$

Where U is the semi-vertical angle of a right cone having the base $R-r$ and a slant 60 length equal to $R \sec \alpha$.

$$\frac{R \tan \alpha \cos U}{3} \times \left(\frac{R-r}{2} \right)^2 \pi = V \quad (8)$$

Where $R \sec \alpha \cos U$ equals the altitude of such a cone. $\cos U$ is derived from (7), and V is the required volume. It follows that the ratio between the volumes of a logarithmic spiral tube of circular vectorial 70 section and a right cone of equal base area and equivalent length would be represented by the formula:—

$$\frac{R+r}{2} \text{ or } \frac{R+r}{2 R \cos U} \quad (9)$$

I claim:

1. In a sound amplifier, a member having a sound amplifying chamber formed therein 80 the boundaries of which are logarithmically developed spiral curves.

2. In a sound amplifier, a member having logarithmic spirally curved walls wherein the angle formed by any tangent to the 85 curve and a radius vector to the point of tangency is constant and lies between the values of 75 degrees and 83 degrees.

In testimony whereof, I have signed my name to this specification this 21st day of 90 September, 1923.

HENRY S. SATTERLEE.
